DISPLAY HANGER FOR HOSIERY

Allen I. Field, 147 Valley Stream Road, Larchmont, N.Y.
10538, and Sidney P. Field, 226 Beach 134th St., Belle
Harbor, N.Y. 11694

Filed Oct. 2, 1968, Ser. No. 13,819

Term of patent 14 years

Int. Cl. D6—07

U.S. Cl. D80—8

FIG.1

FIG. 1 is a top plan view of a display hanger for hosiery showing our new design;

FIG. 2 is a front elevational view thereof;

FIG. 3 is a bottom plan view thereof; and

FIG. 4 is an elevational view taken from the right end thereof.

We claim:

The ornamental design for a display hanger for hosiery, substantially as shown.
